UNITED STATES PATENT OFFICE.

LANSING ONDERDONK, OF NEW YORK, N. Y., AND RUSSEL G. WOODWARD, OF WAUKEGAN, ILLINOIS, ASSIGNEES TO THE UNION SPECIAL MACHINE COMPANY, OF CHICAGO, ILLINOIS, A CORPORATION OF ILLINOIS.

SEWING-MACHINE.

1,116,726.

Specification of Letters Patent.

Patented Nov. 10, 1914.

Application filed July 23, 1902. Serial No. 116,613.

To all whom it may concern:

Be it known that we, LANSING ONDERDONK and RUSSEL G. WOODWARD, citizens of the United States, residing at New York city, 5 in the county of New York, State of New York, and Waukegan, county of Lake, State of Illinois, respectively, have invented certain new and useful Improvements in Sewing-Machines, of which the following is a 10 description, reference being had to the accompanying drawing, and to the letters and figures of reference marked thereon.

Our invention relates to an improvement in sewing machines, and particularly to machines of the type illustrated in our Patent 15 No. 837,106, granted March 27th, 1906.

The object of the invention is to provide a novel presser foot for use preferably in such machines, although it will be understood that it may be used in machines of 20 other types.

The invention consists in the parts and arrangements hereinafter described and pointed out in the appended claims.

25 The invention is illustrated in the accompanying drawings, in which—

Figure 1 is a side elevation of a sewing machine constructed in accordance with our invention; Fig. 2 is a cross section taken 30 through the bed of the machine, showing the trimmer, feeding mechanism and presser foot in side elevation. Fig. 3 is a detail perspective view of the presser foot, and stitch forming elements, and illustrating the trimmer knife, and Fig. 4 is a detail view of the 35 presser foot, taken from the opposite side from that on which Fig. 3 is taken. Fig. 5 is a perspective view of the stitch finger and its supporting means.

40 In these drawings, A is the bed plate, B the standard, C the goose neck, D the needle lever, E the needle bar, F the needle bar supporting gate or frame.

G is the driving shaft carrying in its outer 45 end the belt pulley H, to which power is applied and through the usual eccentric strap I, motion is transmitted to the needle lever D.

The stitch forming elements of the machine are herein shown as comprising the 50 vertically reciprocating thread carrying eye pointed needle 1, which carries a thread down through the material, and in its upward movement throws out a loop, which

loop is seized by a spreader or looping hook 55 S and carried laterally to a point above the cloth plate of the machine, where it is engaged by an oscillating looper L mounted on a shaft M supported entirely above the cloth plate of the machine, which shaft is oscillated to carry a loop of thread through the needle loop and into position to be engaged by the needle in its next descent.

The feeding mechanism is shown clearly in Fig. 2 and it is desirable in machines of 60 this character to crowd the goods toward the needle before the stitching takes place to prevent puckering after the stitches have been passed through the fabric, and the feed dog 29 is, therefore, inclined, and so arranged 65 that as it is lifted that part of it ahead of the needle will catch the goods first. The inclination of the feed dog may be varied, as desired, by mechanism not necessary to herein specifically describe. 70

The trimming device is arranged to act 75 ahead of the stitch forming mechanism to trim off the edge of the fabric to prepare said edge for the reception of the stitches and in the present machine the trimmer 80 comprises an upper reciprocating trimmer knife and a lower co-operating stationary knife, which two knives when brought together, have a shearing action on the goods.

The presser foot 93 in this machine is of 85 novel construction. The foot portion 94 is hinged to the presser foot shank in the usual way and is normally depressed by the spring 95, which bears on the angle piece 90 pivoted to the shank of the presser foot, the spring 90 90 being attached to the screw 96 passing through the arm 97 projecting from the presser foot shank.

A tongue 98 over which the stitches are formed, is rigidly attached through the upwardly extending plate 92 and screw 99, to the presser foot shank. It will be seen, therefore, that the forward spring pressed end of the presser foot coacts with the inclined feed dog and that in the operation 100 of the machine, stitches are formed over the tongue 98 which does not partake of the rocking movement of the bottom or shoe of the foot and are fed off said tongue, in the feeding movement. 105

Attached to the rocking portion of the foot by a screw α , is a transverse projecting plate 100, having a slot 101 for the passage

of the knife, and having a deflecting rear portion 102 which, as the presser foot moves vertically under the action of the feed dog, will crowd the trimmed off strip down 5 through the opening in the cloth plate through which the waste material passes off the plate of the machine.

Various minor modifications and changes in the construction of the parts may be 10 made, without departing from the spirit of our invention.

Having thus described our invention, what we claim and desire to secure by Letters Patent, is:—

- 15 1. In an overseaming machine stitch forming mechanism including means for carrying a thread laterally across the seam, a presser foot having a hinged foot portion and a rigid tongue independent of the hinged portion over which the stitches are formed; substantially as described.
- 20 2. An overseaming machine including means for carrying a thread laterally across the seam, and a presser foot having a hinged spring pressed forward portion and a rigid tongue independent of the spring pressed forward portion, over which the stitches are formed; substantially as described.
- 25 3. An overseaming machine, stitch forming mechanism, including means for carrying a thread laterally across the seam, a presser foot having a hinged spring pressed forward portion and having a rigid tongue secured to the shank of the presser foot and independent of the spring pressed forward portion; substantially as described.
- 30 4. An overseaming machine including in combination, means for carrying a thread laterally across the seam, a presser foot including a forward portion, means for pivotally supporting the same, yielding means for holding said forward portion in contact with the material, and a feed dog inclining downwardly from front to rear, and adapted to engage the material in advance of the needle and crowd it toward the same, said inclined feed dog being so disposed as to cooperate with the forward pivoted portion of said presser foot.
- 35 5. An overseaming machine including stitch forming mechanism having means for carrying a thread laterally across the seam, a presser foot including a forward portion, means for supporting the same, and means for holding said forward portion yieldingly in contact with the material, an inclined feed dog with which said yield-

ing forward portion of the presser foot co-acts, and a rigid tongue independent of the yielding forward portion of the presser 60 foot over which the stitches are formed.

6. In a sewing machine having a cloth plate provided with an opening, the combination with a trimmer, and a feeding device, a presser foot having a pivoted front portion provided with a deflector which operates as the presser foot falls with the feed to force the trimmed off strip out of the line of the seam through said opening; substantially as described.

7. A sewing machine presser foot having a rigid shank with a tongue over which the stitches are formed secured thereto, a pivoted forward portion which co-operates with the feed, said portion being normally spring pressed downwardly, said presser foot having also a transverse deflecting plate to deflect the trimmed off strip; substantially as described.

8. The herein described presser foot, comprising the rigid shank, the forward portion hinged thereto in rear of the needle, a pivoted arm bearing upon the pivoted portion in advance of the needle, a spring bearing upon said pivoted arm; substantially as described.

9. The herein described presser foot, comprising the rigid shank, the forward portion hinged thereto in rear of the needle, a pivoted arm bearing upon the pivoted portion 90 in advance of the needle, a spring bearing upon said pivoted arm and a tongue over which the stitches are formed, rigidly attached to the presser foot shank; substantially as described.

10. The herein described presser foot, comprising the rigid shank, the forward portion hinged thereto in rear of the needle, a pivoted arm bearing upon the pivoted portion 100 in advance of the needle, a spring bearing upon said pivoted arm, and means for adjusting the spring; substantially as described.

In testimony whereof we affix our signatures, in presence of two witnesses.
